CLAIM

The ornamental design for a display screen with an animated graphical user interface, as shown and described.

DESCRIPTION

FIG. 1 is a front view of a first image in a sequence of a display screen with an animated graphical user interface, showing an embodiment of our new design; FIG. 2 is a second image of the embodiment; FIG. 3 is a third image of the embodiment; FIG. 4 is a fourth image of the embodiment; FIG. 5 is a fifth image of the embodiment; FIG. 6 is a sixth image of the embodiment; FIG. 7 is a seventh image of the embodiment; FIG. 8 is an eighth image of the embodiment; FIG. 9 is a ninth image of the embodiment; FIG. 10 is a tenth image of the embodiment; and, FIG. 11 is an eleventh image of the embodiment.

The appearance of the animated user interface sequentially transitions between the images shown in FIGS. 1-11. The process or period in which one image transitions to another image forms no part of the claimed design.

The outermost broke line rectangles show the display device and display screen and all other broken lines show portions of the graphical user interface. All broken lines form no part of the claimed design.

1 Claim, 11 Drawing Sheets
